7 Claims. (Cl. 328—229)

The present invention relates generally to the formation of pulsed beams of electrically charged particles, and more particularly to an improved method and apparatus for accomplishing same.

Pulsed beams of electrically charged particles are extensively employed for a variety of purposes in nuclear research, electronics, and various related fields. In the operation of various particle accelerators, for example, it is often times necessary that a continuous charged particle beam be pulsed prior to introduction to an electric or magnetic accelerating field in order for the particles to be successfully accelerated. Moreover, in a wide variety of nuclear experiments, e.g., neutron time-of-flight experiments, it is desirable that a particle beam impinging on a nuclear target to initiate certain nuclear events be pulsed with extreme precision such that the occurrence of the events can be accurately determined with respect to time.

While many of the present day charged particle accelerators are capable of producing precisely formed short duration pulses of charged particles in their normal operation, it is often times desirable that a machine of the type that normally produces only a continuous particle beam be selectively adaptable to precision pulsed operation for the sake of versatility. For example, at installations having only a continuous beam machine available, the provision of means for pulsing the beam resourcefully facilitates the performance of time-of-flight experiments as well as a variety of other additional experiments which could not otherwise be conducted with the single continuous beam machine. Moreover, it is often desirable that beam pulsing means be employed with pulsed machines in order to pulse the pulsed beam at a repetition rate different than the normal operating repetition rate, i.e., to chop the normal beam pulses.

Conventional radio frequency sweeper systems, i.e., systems wherein a continuous beam is directed between a pair of deflection plates energized with radio frequency voltage and a fixed portion of the deflected beam is collected each radio frequency cycle while the remainder is transmitted, are commonly employed to pulse a continuous beam. Such systems are variously inadequate, however, for purposes of optimum flexibility and performance. In such a system the pulse width is only controllable over an extremely narrow range and the repetition rate is fixed. Moreover, due to the sinusoidal configuration of the radio frequency energizing voltage, the shape of the beam pulses are not rectangular, but Gaussian, and accordingly are terminated with relatively little precision. For the same reason, symmetry between consecutive pulses is difficult to obtain and maintain.

Considerable advantage is therefore to be gained by the provision of a highly flexible beam pulsing method and means for producing, from a continuous particle beam, rectangular pulses which are always consecutively of the same shape. Other advantages will be realized where the beam pulsing method and means include varia-

ble pulse width and repetition rate capabilities over extremely wide ranges.

The present invention provides a method and apparatus which accomplish the foregoing and thereby overcomes many of the limitations and advantages of prior art beam pulsing systems. More particularly in the beam pulsing method of the invention a continuous beam of electrically charged particles (i.e., ions or electrons) which may be produced for example by a particle accelerator are directed between a pair of spaced deflection plates. Provision is made for the deflection of the beam to one side of the beam traverse axis between the plates by establishing a unidirectional electrostatic field therebetween. The deflected beam may then be collected as by disposing a collector electrode transversely on one side of the axis so as to intercept the deflected beam. The electrostatic field, however, is repetitively neutralized during precise time intervals by successively applying a train of substantially flat front voltage pulses to one of the deflection plates with the pulses being of equal magnitude and opposite direction with respect to the electrostatic field, and then after a time delay, to the other deflection plate. The beam is not deflected during the neutral interval of the electrostatic field and is not collected but directed axially past the collector electrode to emerge as a pulsed beam. Moreover, since the same flat pulse front is employed to initiate as well as terminate each neutral electrostatic field interval between the deflection plates, the resulting beam pulses are consistently rectangular and of precise time durations. The precisely formed pulsed beam may be further shaped as by passing same through a buncher cavity and then employed as desired.

The invention also provides apparatus in which the foregoing method may be conducted, such apparatus comprising in general means for providing the indicated unidirectional electrostatic field between the spaced deflection plates, means for collecting the deflected charged particle beam, means for generating the flat front voltage pulses, and means for applying said pulses directly to one deflection plate and after a time delay to the other deflection plate. Accessory apparatus for utilizing the pulsed beam is also provided.

Accordingly, it is an object of the present invention to provide a method and apparatus for pulsing a continuous beam of electrically charged particles.

Another object of the invention is the provision of a charged particle beam pulsing method and apparatus for producing precisely formed beam pulses having durations which may be varied over an extremely wide range.

It is still another object of the invention to produce charged particle beam pulses at a repetition rate which is variable over an extremely wide range.

An important object of the invention is to provide a pulsed beam of charged particles having equal symmetry between consecutive pulses.

Yet another object of the invention is to provide an optimumly focused pulsed beam of charged particles.

A further object of the invention is the provision of a highly flexible system for producing substantially rectangular beam pulses of charged particles in a charged particle accelerator.

Additional objects and advantages of the invention will become apparent from the following description and claims considered together with the accompanying drawing, of which:

Figure 1 is a graphical illustration of voltage pulses and the manner in which they are applied to beam deflection plates in the present invention; and

Figure 2 is a schematic block diagram of preferred apparatus for conducting the method of the invention as

embodied as a beam pulsing system for a charged particle accelerator.

Considering now the method of the present invention in some detail with reference to the accompanying drawing, it is contemplated that there will first be provided in the initial steps of the method a continuous beam of electrically charged particles, i.e., electrons or ions, which may be produced for example in various continuous beam charged particle accelerators. The continuous beam is deflected laterally of the normal axial direction of beam motion preferably by subjecting the beam to a unidirectional electrostatic field established at right angles to the beam axis. The above-noted electrostatic field may be provided as by disposing deflection plates on opposite sides of the beam in equal spaced relationship therefrom, i.e., the continuous beam is directed axially between the spaced deflection plates. The term axially is taken herein as referring to the beam traverse axis emanating from the source of charged particles. A constant unidirectional potential gradient is then established between the deflection plates to thus establish the unidirectional electrostatic field. As regards the establishment of the potential gradient, it will be appreciated that several alternatives are possible, and in this connection one alternative consists in biasing one plate with a positive direct current voltage as indicated by curve *a* of Figure 1, while leaving the other plate with zero bias.

Subsequent to the deflection of the continuous charged particle beam, the deflected beam may be intercepted and collected. The foregoing is preferably accomplished by disposing a collector electrode laterally of the original beam direction and positioned to receive the deflected beam after passage between the deflection plates. The deflected continuous beam is accordingly terminated at the collector electrode and, in the absence of further operation upon the beam, is not transmitted beyond such collector electrode.

In the method of the present invention a pulsed beam is formed by periodically neutralizing the aforementioned electrostatic beam deflecting field for precise increments of time. During such increments of neutralized field, the particle beam is not deflected and accordingly not intercepted at the collector electrode, but instead is transmitted axially past the electrode. Consequently as the beam is periodically swept from the collector electrode to the axial direction by-passing the electrode by virtue of the periodically neutralized field, a series of beam pulses having durations substantially equal to the precise neutralizing time increments emerge axially beyond the collector electrode.

The foregoing periodic neutralization of the electrostatic deflection field is accomplished with extreme precision with respect to time preferably by first providing a train of substantially flat front and crest voltage pulses *b* (e.g., trapezoidal or rectangular pulses) having amplitudes equal to the strength of the electrostatic field. The voltage pulses are best provided at an adjustable repetition rate as by means of variable rate pulse generating means in order that the beam pulse repetition rate may be correspondingly varied. Each pulse *b* is applied to the electrostatic field in opposition to the direction thereof as by applying the pulses in negative relationship to the positively biased one of the deflection plates. The resulting voltage distribution at the biased deflection plate is consequently as depicted by curve *c* of Figure 1. As shown therein, the voltage abruptly changes from the positive bias maintained thereon (curve *a*) to zero upon the occurrence of an applied pulse *b*. More particularly, the electrostatic field due to bias *a* is neutralized by pulse *b* in a time equal to the rise time *t_r* of the front of such negative going pulse. Accordingly, in order that the corresponding beam pulse fronts resulting from the foregoing neutralizing action be as precisely formed as possible, it is necessary that the

front of each pulse *b* be as vertical as possible, viz., *t_r* should be extremely small.

Each pulse *b* is additionally applied to the electrostatic field in aiding relationship to the direction thereof after an adjustable time delay *t_d* less than the duration of the flat crest (i.e., the positive or negative peak) of the pulse. The foregoing may be accomplished as by applying each pulse *b* produced by the previously mentioned pulse generating means in negative relationship to the electrically unbiased deflection plate through a suitable variable time delay line to introduce the time delay *t_d*. The resulting voltage distribution at such electrically unbiased deflection plate is thus as illustrated by curve *d* of Figure 1. The voltage abruptly changes during rise time *t_r* of the vertical front pulse *b* from zero potential to the negative amplitude (negative crest) of such pulse which is equal to the magnitude of bias *a*. Moreover, inasmuch as pulse *b* is applied to the unbiased plate after the time delay *t_d*, the voltage as such unbiased plate with respect to the application of pulse *b* to the biased plate, abruptly changes after such time delay *t_d* to thereafter reach the negative value of bias *a* after rise time *t_r*.

The resultant voltage distribution existing between the deflection electrodes as obtained by a summation of the individual plate voltage distributions *c* and *d*, respectively, accordingly comprises a series of negative pulses *e* deviating essentially from positive bias *a* to zero voltage as illustrated by curve *f* of Figure 1. It is to be noted that each pulse *e* is symmetrical in that the rise and fall times of the pulse are identical. This is due to the fact that the front of the same applied pulse *b* is employed to drive the voltage between the deflection plates from zero to the magnitude of positive bias *a* as was previously employed to drive the voltage from positive bias *a* to zero. It will be further noted that the negative crest width *t_b* of each pulse *e*, where *t_b=t_d-t_r* determines the time during which the voltage between the plates is zero, viz., the time during which the electrostatic deflection field is neutralized and the beam is undeflected to form a beam pulse. The width of the beam pulses may accordingly be varied by varying the delay time *t_d* between applications of each one of the pulses *b* to first one and then the other of the deflection plates.

Preferred apparatus for conducting the foregoing method of the present invention is illustrated in Figure 2 of the drawing wherein such apparatus is embodied as a system for pulsing the beam of a continuous beam charged particle accelerator 11. The resulting pulsed beam is then employed to bombard a suitable target 12 disposed in axial alignment with accelerator 11 to produce precise pulses of neutrons as for the purpose of time-of-flight studies.

More specifically, the preferred apparatus of the invention will include means for deflecting the output beam of accelerator 11 away from target 12 and such means preferably comprises a pair of flat deflection plates 13, 14 equally spaced on opposite sides of an axial path between the accelerator beam extraction structure and target. While plates 13, 14 may be diametrically opposed, it is more preferable that the plates 13, 14 be disposed in axially staggered relationship with grounded plates 16, 17, respectively, spaced in diametric opposition therefrom. The latter arrangement minimizes undesirable capacitative effects that exist with the former arrangement of the deflecting plates in diametric opposition.

In order to bias deflection plates 13, 14 and establish a unidirectional electrostatic field therebetween, a suitable D.C. voltage supply 18 is connected to one plate 13 and the other plate 14 is unbiased. It will be appreciated that plate 13 may be biased either positively or negatively, however, in the interest of consistency with the examples previously described in relation to the method of the invention, plate 13 is positively biased by connection to the positive terminal of voltage supply 18. The

resulting electrostatic field between plates 13, 14, 16, 17 thus deflects the beam from accelerator 11 laterally of the axial path between the accelerator and target 12.

Beam collecting means are preferably disposed in receiving relationship to the deflected beam and such means is best provided as a collector electrode 19 disposed between plates 13, 14 and target 12. Electrode 19 is transversely oriented and closely spaced laterally of the axial path between accelerator 11 and target 12 in order to intercept the deflected beam and dissipate the energy of same. Various equivalent collecting means may also be utilized to intercept the deflected beam, for example, a centrally apertured plate may be coaxially disposed between the accelerator and target.

As regards the electrostatic field neutralizing pulses of previous mention, such pulses are provided by any suitable pulse generating means 21 for applying substantially vertical front-flat crest pulses to deflection plate 13 and, after a time delay, to plate 14. More particularly, pulse generating means 21 preferably includes a square wave generator 22, e.g., a free running multivibrator, the repetition rate of which may be varied over a wide range. Square wave generator 22 functions as the rate generator for the beam pulsing system and may be synchronized in the conventional manner with an externally generated injection signal. The output of square wave generator 22 is coupled to a differentiator 23 which may be conventionally provided, for example, as a series capacitor and shunt resistor. Differentiator 23 is effective in producing a series of alternately positive and negative spikes which respectively correspond to the leading and trailing edges of the square wave pulse from square wave generator 22.

The output of differentiator 23 is coupled to a shaper and inverter 24 which is advantageously selected as one having parallel outputs 26, 27. For optimum performance, shaper and inverter 24 is arranged to produce substantially vertical front and flat crest output pulses, e.g., unsymmetrical trapezoidal pulses having fast rise times of the order of 10^{-8} seconds, in response to the positive spikes applied thereto from differentiator 23, the negative spikes being eliminated. The pulses are additionally inverted in the shaper and inverter whereby the output at each of parallel outputs 26, 27 comprises a series of negative substantially vertical front and flat negative crest unsymmetrical trapezoidal pulses occurring at the repetition rate of square wave generator 22. It is to be appreciated that many circuits are well known in the electronics art for accomplishing the purposes of shaper and inverter 24, and therefore no specific circuit is described nor illustrated herein.

One output 26 of shaper and inverter 24 is directly connected to a variable bias pulse amplifier 28, the output of which is coupled to positively biased deflection plate 13. The other output 27 of the shaper and inverter is connected through suitable pulse delay means, e.g., a variable time delay line 29, to a similar pulse amplifier 31. The output of the latter amplifier 31 is in turn coupled to the unbiased deflection plate 14. Identical substantially vertical front and flat negative crest pulses are thus applied first to deflection plate 13 and then, after a time delay introduced by delay line 29, to deflection plate 14. Moreover, the bias of amplifiers 28, 31 may be varied to adjust the amplitude of the output pulses therefrom equal to the magnitude of the bias supplied by voltage supply 18. The resulting pulses are accordingly of the character illustrated as pulses *b* in Figure 1 of the drawing and hereinbefore described in conjunction with the method of the present invention. The pulses therefore are effective in neutralizing the electrostatic deflection field between deflection plates 13, 14, and ground plates 16, 17, respectively for precise increments of time determined by the delay time of delay line 29 and occurring at the repetition rate of square wave generator 22. During the neutral time increment the beam from accelerator 11, which

is normally deflected and intercepted by collector electrode 19, is abruptly swept from such electrode to the axial path between the accelerator and target 12. Consequently, precisely formed beam pulses occurring at the repetition rate of square wave generator 22 are directed toward target 12. It is to be appreciated, moreover, that an electrostatic lens effect is produced by the field configuration established between deflection plates 13, 14 and ground plates 16, 17. During the neutral time interval the individual fields between plates 13 and 16, and 14 and 17, respectively, which in combination establish the resultant field of zero strength, tend to focus the beam upon target 12. Conversely, the beam is defocused during the remainder of the time when deflected by the field for collection by collector electrode 19. Such defocusing of the beam at the collector facilitates dissipation of the beam energy thereat over a relatively wide surface area resulting in minimized burning of the collector electrode and an attendant decrease in the frequency with which same must be replaced. The pulsed beam of the present invention may accordingly be said to be optimally focused in as much as the portions of the beam useable at the target 12 are concentrated as pulses of increased current density while the unused portions of the beam are dispersed as pulses of decreased current density for collection at the collector electrode 19 resulting in optimum dissipation of the beam energy thereat. It is to be appreciated, however, that in some instances where a reduction in the current density of beam pulses incident upon the target 12 is desirable in order to facilitate more efficient dissipation of the beam energy at the target, the beam may be defocused in passage toward target 12 and focused in passage toward collector electrode 19 by applying pulses from amplifier 28, 31 to deflection plates 13, 14 in a manner opposite to that illustrated in the drawing and hereinbefore described.

In some instances it is desirable that the beam pulses directed at target 12 be further bunched or shortened in time duration prior to impingement on the target. To accomplish the foregoing a buncher cavity 32 may be disposed between collector electrode 19 and target 12 in axial alignment with the path between the target and accelerator 11. Buncher cavity 32 is designed to resonate at a frequency corresponding to the repetition rate of the beam pulses or a multiple thereof and is energized by a radio frequency source (not shown) in the conventional manner. The radio frequency signal is applied at the frequency of the pulsed beam or at a multiple thereof to velocity modulate the beam pulses. In this connection it is necessary that the beam pulses be in proper phase with the radio frequency modulating signal, and to accomplish this purpose square wave generator 22 is synchronized to the modulating signal as by connecting a conductor 33 between buncher cavity 32 and the injection input of the square wave generator. The velocity modulated pulses emerging from the buncher cavity 32 in drifting through the field free space between the buncher and target 12 then form shorter bunches in impingement with the target.

As regards the adjustment of various of the characteristics of the pulsed beam produced by the above described apparatus of the present invention, it is to be noted that the repetition rate of the beam pulses may be varied over a considerable range by correspondingly varying the repetition rate of square wave generator 22. In this connection conventional square wave generators are readily available which may be employed as generator 22 to correspondingly produce beam pulses at readily attainable repetition rates in a range of the order of from 1 pulse per second to several million pulses per second. In addition the beam pulses may be employed to produce a bunched beam having an even shorter time duration by utilizing a modulating frequency at buncher cavity 32 which is a multiple of the repetition rate of square wave generator 22.

The duration of the beam pulses is also continuously

adjustable over a wide range by variation of the delay time t_d of delay line 29 inasmuch as the pulse negative crest duration t_p is substantially given by the expression: $t_p = t_d - t_r$, as hereinbefore described. With conventional equipment employed as shaper and inverter 24 and pulse amplifiers 28, 31, rise times t_r of the order of 10^{-8} seconds are easily attainable in practice for the pulses applied to deflection plates 13, 14. Moreover, delay lines are commonplace in the art which may be employed as delay line 29 to produce time delays in a range of the order of 10^{-6} to 2×10^{-8} seconds whereby an adjustable range of beam pulse durations of the order of 10^{-6} to 10^{-8} seconds is easily attainable in practice.

While the present invention has been hereinbefore described in terms of specific steps in the method and with respect to a single embodiment, it will be apparent that numerous modifications and variations are possible within the spirit and scope of the invention and thus it is not intended to limit the invention except by the terms of the following claims.

What is claimed is:

1. Apparatus for pulsing a continuous beam of electrically charged particles comprising deflection plate means equally spaced on opposite sides of the axis of beam traverse, bias means connected to said deflection plate means for establishing a unidirectional electrostatic field at right angles to said axis to deflect said beam laterally thereof, pulse generating means for generating unidirectional vertical front and flat crest electrostatic field neutralizing pulses, and means connecting said pulse generating means to said deflection plate means for successively applying said pulses to said deflection plate means in opposed relationship to the direction of said electrostatic field and after a time delay in aiding relationship to the direction of said field whereby a pulsed beam is produced along said axis.

2. Apparatus as defined by claim 1 further defined by said deflection plate means comprising a pair of deflection plates equally spaced on opposite sides of said axial path of motion and disposed in axially staggered relationship, and a pair of grounded plates equally spaced on opposite sides of said axial path of motion in diametric opposition to said deflection plates.

3. Apparatus as defined by claim 1 further defined by said means connecting said pulse generating means to said deflection plate means comprising a conductor and a time delay line commonly coupled to said pulse generating means and respectively coupled to said deflection plate means.

4. Beam pulsing apparatus comprising a pair of axially staggered deflection plates equally spaced on opposite sides of an axial path of motion of a continuous beam of electrically charged particles, a pair of grounded plates equally spaced on opposite sides of said axial path of motion in diametric opposition to said deflection plates, a D.C. voltage supply connected to one of said deflection plates for establishing an electrostatic field to deflect said beam laterally of said axial path of motion, beam collecting means spaced from said axial path of motion and disposed in receiving relationship with the laterally deflected beam, pulse generating means having a pair of parallel outputs for producing repetitiously occurring unidirectional vertical front and flat crest electrostatic field neutralizing pulses, the first of said parallel outputs directly coupled to one of said deflection plates to apply said pulses in opposition to the direction of said electrostatic field, and a time delay line connected between said second parallel output and said second deflection plate to apply said pulses in aiding relationship to the direction of said electrostatic field whereby beam pulses having durations substantially equal to the delay time of said time delay line emerge beyond said beam collecting means on said axial path of motion.

5. In a system for producing a pulsed charge particle beam at a target, the combination comprising a charged

particle accelerator disposed in axial alignment with said target, deflection plate means disposed between said accelerator and said target and oppositely spaced transversely from an axial path therebetween, a D.C. power supply connected to said deflection plate means for establishing a unidirectional electrostatic field transverse to said axial path, beam collecting means transversely disposed between said deflection plate means and said target and spaced from said axial path, pulse generating means for generating unidirectional vertical front and flat crest voltage pulses, means connecting said pulse generating means to said deflection plate means in opposite sense to the direction of said electrostatic field, time delay means connecting said pulse generating means to said deflection plate means in aiding relationship to the direction of said electrostatic field whereby beam pulses having durations substantially equal to the time delay of said time delay means are produced along said axial path and a buncher cavity disposed in alignment with said axial path and between said beam collecting means and said target for velocity modulating the beam pulses.

6. Apparatus for pulsing the beam of a continuous beam charged particle accelerator comprising a pair of deflection plates disposed in axially staggered relationship on opposite sides of a path in axial alignment with said accelerator, a pair of ground potential plates respectively disposed in diametric opposition to said deflection plates on opposite sides of said path therefrom, a positive D.C. voltage source connected to the first one of said deflection plates for applying a D.C. bias voltage thereto, a collector electrode transversely disposed in lateral spaced relationship from said path on the distal side of said deflection plates with respect to said accelerator, variable repetition rate negative pulse generating means for producing vertical front and flat negative crest voltage pulses having amplitudes equal to the magnitude of said D.C. bias voltage, said pulse generating means having a pair of parallel outputs, means directly coupling one of said outputs to said first deflection plate, and a variable time delay line coupling said second output to said second deflection plate whereby the beam of said accelerator is precisely pulsed at the repetition rate of said pulse generating means and for durations substantially equal to the delay time of said time delay line.

7. In a charged particle accelerator for bombarding an axially aligned target with substantially rectangular beam pulses of adjustable time duration and at a variable repetition rate, the combination comprising first and second flat deflection plates disposed in axially staggered relationship and equally spaced on opposite sides of an axial path between said accelerator and said target, a pair of ground potential plates respectively disposed in diametric opposition to said deflection plates on opposite sides of said axial path, a positive D.C. voltage source connected to said first deflection plates for applying a D.C. bias voltage thereto, a collector electrode transversely disposed in laterally spaced relationship from said path between said deflection plates and said target, a variable repetition rate square wave generator, a differentiator connected to the output of said generator for producing a series of alternately positive and negative spikes, a shaper and inverter connected to the output of said differentiator and having first and second outputs in parallel, said shaper and inverter producing at said first and second outputs identical vertical front and flat negative crest pulses in response to said positive spikes, a variable bias pulse amplifier connected between said first output and said first deflection plate, a variable time delay line connected to said second output, a second variable bias pulse amplifier connected between said time delay line and said second deflection plate, a buncher cavity coaxially disposed with respect to said axial path between said collector electrode and said target for velocity modulating a charged particle beam, and conductor means connected between said buncher cavity and said square

wave generator for injecting synchronizing signals from said cavity to said square wave generator.
